ATTORNEY.

UNITED STATES PATENT OFFICE.

WILLIAM E. WITTENBROCK, OF SAN FRANCISCO, CALIFORNIA.

DESIGN FOR A DRAPERY CORNICE.

Application filed March 14, 1928. Serial No. 25,849. Term of patent 14 years.

To all whom it may concern:

Be it known that I, WILLIAM E. WITTENBROCK, a citizen of the United States, residing at 26 Brunswick Street, city and county of San Francisco, State of California, have invented a new, original, and ornamental Design for a Drapery Cornice, of which the following is a specification, reference being had to the accompanying drawing, forming part thereof.

Figure 1 is a front view of the complete de-

sign and showing part of the repeating design,

Figure 2 is an edge view of the design shown in Figure 1.

The article forms the front of a pole for supporting curtains and draperies.

I claim:

The ornamental design for a drapery cornice, as shown and described.

WILLIAM E. WITTENBROCK.
